UNITED STATES PATENT OFFICE

166,424

PLAY SHOE OR THE LIKE

Carl R. Stern, Garden City, N. Y.

Application February 6, 1952, Serial No. 18,404

Term of patent 7 years

(Cl. D7—7)

To all whom it may concern:

Be it known that I, Carl R. Stern, a citizen of the United States of America, residing at Garden City, county of Nassau, and State of New York, have invented a new, original, and ornamental Design for a Play Shoe or the like, of which the following is a specification, reference being had to the accompanying drawing, forming part thereof,

Fig. 1 is a top plan view of a play shoe or the like showing my new design, and

Fig. 2 is a side elevational view thereof.

I claim:

The ornamental design for a play shoe or the like, substantially as shown.

CARL R. STERN.
